UNITED STATES PATENT OFFICE.

WALTER W. STOPPLE, OF ESCANABA, MICHIGAN, ASSIGNOR TO A. J. KIRSTIN COMPANY, OF ESCANABA, MICHIGAN, A CORPORATION OF MICHIGAN.

STUMP-PULLER.

1,380,748.

Specification of Letters Patent. Patented June 7, 1921.

Application filed April 12, 1920. Serial No. 373,357.

To all whom it may concern:

Be it known that I, WALTER W. STOPPLE, a citizen of the United States, and resident of Escanaba, in the county of Delta and 5 State of Michigan, have invented new and useful Improvements in Stump-Pullers, of which the following is a description, reference being had to the accompanying drawings, which are a part of this specification.

10 The invention relates to stump pullers, and more particularly to that type of puller in which a drum is rotated by a sweep.

One of the objects of this invention is to provide a simple and efficient mounting for 15 the drum in the frame of the machine so that the friction of the rotating drum may be reduced to take the heavy drag off of the draft animal operating the device.

20 A further object of the invention is to provide an efficient form of clutch for the drum whereby the drum may be secured to the sweep in a plurality of positions, thereby making it easy to throw the machine in and out of gear.

25 A further object of the invention is to provide a sweep trough for a machine of this type which will readily accommodate sweeps of different dimensions.

30 A further object of the invention is to provide effective means for holding the drum pawl out of engagement with the drum ratchet, when desired, and which means may be readily released by the operator to throw in the pawl.

35 A further object of the invention is to provide a cable connection between the frame of the machine and the anchor stump of such a character that all stress produced on the frame during the winding up of the cable on the drum will be transmitted in substantially 40 a straight line through the anchor cable to the anchor stump.

45 The invention further consists in the several features hereinafter set forth, and more particularly defined by claims at the conclusion hereof.

In the drawings: Figure 1 is a perspective view of a stump puller embodying the invention; Fig. 2 is a plan view thereof; Fig. 3 is a section taken on the line 3-3 of Fig. 50 2; Fig. 4 is a section taken on the line 4-4 of Fig. 3, the clutch being in; Fig. 5 is a detail sectional view showing the pawl-locking and releasing mechanism; Fig. 6 is a bottom view of the drum.

55 In the drawings the numeral 7 designates

the sweep, 8 a sweep trough, 9 the drum mounted in the frame 10 and provided with a ratchet 11 coöperating with a pawl 12, said frame being usually mounted on skids 13.

The sweep trough 8 is provided near its 60 end with curved guide grooves 14 to receive large U-bolts 15 which carry plates 16 whereby the sweep 7, disposed in the trough, may be secured in any longitudinal position with respect thereto by clamping the sweep 65 between the trough and the plates 16 on screwing up the nuts 17 upon the U-bolts 15. The grooves 14 in the trough effectually prevent any slippage of the U-bolts 15 with respect to the trough, and by the means thus described the sweep is securely clamped to the trough. The trough is provided with a tubular hub portion 18 which passes down through the hardened steel sleeve bearing 19 mounted in an opening 20 in the frame 70 10 and connects with a spindle portion 21 of the sweep, the lower portion 22 of this spindle being free to rotate in a hardened steel ring 23 having a tight pressed fit in an opening 24 of the lower portion of the frame 80 10. The sweep trough is held against vertical movement with respect to the frame by means of a bolt 25, a bearing 26 and the bearing 23, the bolt 25 passing through the bearing 26 and bearing 23 and serving to clamp 85 or hold the bearing 26 against inwardly extending flanges 27 on the spindle 22.

The drum 9 is journaled at its lower end upon the bearing 23 and at its upper end upon the depending portion 28 of the bearing 19. This drum in its bottom is provided with a curved cable receiving and retaining groove 29 communicating with an opening 30 in the bottom of the drum and receiving and securely holding the taper plug end of the cable which passes through the opening 30 of the drum so that the cable may be wound about the curved periphery of the drum. The drum is provided at its upper portion with inwardly extending tooth projections 31 spaced apart to form clutch slots 90 32 and having beveled grooves 33 on one side thereof so as to permit of ready registration of the clutch in any one of the series of diametrically disposed clutch slots 32.

Hub portion 18 of the sweep trough is 105 provided with vertically disposed slots 34 and the spindle portion with vertically disposed slots 35. A clutch shaft 36 passes through the slots 34 and carries a clutch member 37, and eccentric disks 38 at its ends. 110

These eccentric disks have grooved lugs 39 receiving the ends 40 of a U-shaped lever 41, which lever passes up and over the sweep and clears the same so that it may be swung 5 to different positions without interfering with the sweep. The eccentrics 38 are adapted, when rotated, to move the clutch member 37 vertically in the slots 34, the eccentrics through the raising of the clutch member 10 bearing upon the flanged upper end 42 of the bearing 19.

The clutch member 37 consists of a flat-sided block having arms 43 mounted on the shaft 36, and having clutch teeth 44 with 15 one side beveled to coöperate with the beveled notches 33 on the projections 31 of the drum and adapted to enter into the diametrically disposed slots 32 in the drum formed by the projections 31, said clutch 20 block being guided in its downward movement by the slots 35 in the spindle of the sleeve and alined slots 45 in the hub of the sweep.

A pawl 46 is pivotally secured to the 25 frame by pin 47 at the front end thereof so that said pawl is normally held in engagement with one tooth of the ratchet by gravity, the teeth of the ratchet being beveled so as to permit the pawl to move upwardly 30 into engagement with the next tooth when the drum is rotated in one direction by the sweep, the pawl preventing a backward rotation of the drum. When it is desired to let the drum run free the pawl is maintained in raised position by means of a locking latch 48 which is pivotally mounted on a bolt 49 at the free end of the pawl, said latch having a projection 50 coöperating with a stop 51 on the pawl, and a tooth 40 52 coöperating with a stop 53 on the frame of the machine. With this construction when the pawl is moved from its lowered position, as shown in full lines in Fig. 5, and the latch 48 is tipped so as to swing the 45 tooth 52 downwardly, said latch may clear the stop 53 to permit the pawl being raised to a position to clear the ratchet, such as shown by dotted lines on Fig. 5, at which time a release of the latch 48 causes the 50 tooth 52 to engage the stop 53 and the projection 50 to engage the stop 51 to form a lock for holding the pawl in raised position against the weight of the pawl. This construction provides a very simple arrangement 55 for manipulating the pawl, as the operator can lock or unlock the pawl with one hand by a proper movement of the latch 48.

The frame 10 is preferably made in one piece of rectangular formation having up- 60 right sides 54 and 55. Openings 56 are provided near the ends of the upright 55 to receive pins 57, which pins serve to connect the eyed ends 58 of cable sockets 59 secured to short cables 60, both of said cables 60 65 being secured at their other ends to the

common socket member 61 to which a single anchor rope 63 is also secured. This anchor rope 63, as usual, is provided with a hook or other suitable fastening device (not shown) so that it may be fastened to an anchor stump or tree and by reason of the transmission of the pull through the separated cables 60 this pull will be transmitted in a substantially straight line to the anchor cable 63 to thereby prevent tipping 75 the machine while the pull cable 64 is being wound up on the drum, due to the fact that either one or both of the cables 60 transmits this pull to the anchor line in some instances one cable acting as a check on the 80 other. The other upright is provided with a substantially centrally disposed opening 65 to which a power loop cable connection 66 is secured by means of a removable pin 67 passing through the eyed end of the 85 power loop connection 66 to the aperture 65. Where one or more pulleys are used in connection with the pull-rope to dislodge the stump, one of the cables carrying the pulley is secured to this power loop and 90 permits the pulley to be disposed near the ground so that a horse may readily step over the pull-cable in operating the sweep, a feature which is of advantage as compared with the usual construction in which 95 the power pulley is carried by or directly secured to the frame of the machine.

In the operation of this machine the anchor cable 63 is connected to the anchor stump and the cable 64 through suitable 100 connections to the stump to be pulled, said connections including the cables and pulleys attached to the power loop 66 if double or triple power is desired, and then, with the clutch 37 thrown into engagement with 105 the drum and the turning of the drum in the proper direction by the sweep, the cable is wound up on the drum and the stump is loosened from its anchorage in the earth. If at any time during the stump pulling 110 operation it is desired to let the drum run free the clutch block 37 is raised by a shifting of the member 41 which causes the eccentrics 38 engaging the bearing 19 to lift said clutch into inoperative position, as 115 shown in Fig. 3. Furthermore, the drum is loosened from connection with the pawl by raising of the pawl and locking of same, as previously explained.

I desire it to be understood that this invention is not limited to any specific form or arrangement of parts except in so far as such limitations are specified in the claims.

What I claim as new and desire to secure 125 by Letters Patent is:

1. In a stump puller, the combination, with a frame having spaced frame members provided with coaxial openings, of bearing bushings mounted in said openings and ex- 130

tending inwardly beyond the frame members, a drum mounted in the frame and journaled on the extended ends of said bushings, and a sweep trough having a hub portion 5 journalized in one of the bushings and a spindle portion journaled in the other bushing.

2. In a stump puller, the combination of a drum having a series of diametrically arranged radially extending slots, a sweep trough, and a clutch block rotatable with and slidably mounted in and with respect to said trough and adapted to enter any one of the series of diametrically disposed slots in the drum, and means for controlling said 15 clutch block.

3. In a stump puller, the combination of a drum having diametrically disposed radially extending slots, a sweep trough having a hollow hub portion provided with diametrically disposed guide slots, a clutch block slidably mounted in the guide slots and adapted to enter the diametrically disposed slots in the drum, and means for moving said clutch block.

25 4. In a stump puller, the combination, with a frame, of a drum mounted therein and having an interior toothed portion forming clutch slots, a sweep trough having a hollow hub portion and a spindle portion, 30 both of which are provided with aligned guide slots, a clutch block mounted in the hollow hub portion of the trough and slidable in said guide slots and clutch slots, and means for moving said clutch block into and out of 35 the clutch slots.

5. In a stump puller, the combination with a frame having spaced frame members provided with coaxial openings, of bearing bushings mounted in said openings and extending inwardly beyond the frame members, a drum journaled on the extended ends

of said bushings and having a series of diametrically arranged radially extending slots in its hub, a sweep trough having a hollow hub portion journalized in one of said bushings and a spindle portion journaled in the other bushing, the hub portion and spindle portion of the sweep trough having aligned guide slots, a clutch block mounted in the hollow hub portion of the sweep trough and slidable in said guide slots into register with any one of the series of diametrically disposed slots in the drum, and means for operating said clutch block.

6. In a stump puller, a sweep trough 55 member having a channel shaped trough provided with grooves on its outer side, U-bolts seated in said grooves, and clamping plates coöperating with said bolts to adjustably secure the sweep in the trough. 60

7. In a stump puller, the combination, with a frame, of a drum rotatably carried thereby and provided with a ratchet, a dog pivotally mounted on the frame and engageable with said ratchet, said dog being 65 normally held in engagement with said ratchet, and a pivoted latch mounted on the dog and held in engagement with the frame by the weight of the dog, to hold the dog out of engagement with the ratchet. 70

8. In a stump puller, the combination, with a frame, of a drum rotatably carried thereby and provided with a ratchet, a dog pivotally mounted on the frame and engageable with said ratchet and having a 75 stop, and a latch pivotally mounted on the dog and engageable with said stop and said frame when the dog is released from the ratchet to hold the dog in inoperative position.

In testimony whereof I affix my signature.
WALTER W. STOPPLE.
